UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 26,213, dated October 27, 1896.

Application filed July 22, 1896. Serial No. 600,172. Term of patent 3½ years.

To all whom it may concern:

Be it known that I, ALBERT ROSENSTEIN, a citizen of the United States, residing at Lancaster, in the county of Lancaster and State of Pennsylvania, have invented and produced a new and original Design for Cane and Umbrella Handles, of which the following is a specification, reference being had to the accompanying drawings, showing the same.

Figure 1 is a top or outer end view of a handle embodying my design; Fig. 2, an elevation of one side thereof; Fig. 3, a view of the side opposite that shown in Fig. 2, and Fig. 4 a view of one of the panels embraced by said two sides, these four views being deemed necessary to fully illustrate my design.

The leading features of my design consist in a representation of a head of the Goddess of Liberty, with a border surrounding the same, on the outer end of the handle and of the busts of the Republican candidates for the Presidency and for the Vice-Presidency on opposite sides of said handle.

This handle has a knob annular in general outline and having a tapering connection with its stem, in which is the socket for the cane or the umbrella-handle. On the outer end of the knob is a representation of a head of the Goddess of Liberty, with a border surrounding the same. On one side of said handle is 30 a bust of the Republican candidate for the Presidency, shown in relief in a medallion, and on the opposite side of said handle is a bust of the Republican candidate for the Vice-Presidency, also in relief in a similar 35 medallion, while on opposite sides of the handle and between said medallions are fanciful panels. Between the medallions and panels are scrolls and other fanciful corrugations.

A designates the head of the Goddess of 40 Liberty on the end of the handle; B, the bust of the Republican candidate for the Presidency; D, the bust of the Republican candidate for the Vice-Presidency, and E the interposed panels. 45

What I claim is—

The design for a cane or umbrella handle, as shown and described.

ALBERT ROSENSTEIN.
